UNITED STATES PATENT OFFICE

HARRY E. GOUGH, OF OZONE PARK, NEW YORK

HAT BLOCK CONSTRUCTION

Application filed October 30, 1930. Serial No. 492,122.

This invention relates to hat blocks and in particular to a method of making one of the units of a hat block assembly which is more adaptable for the purpose and can be produced at much smaller cost.

A particular object of my invention is to provide in a hat block assembly a band block made in laminated single or plastic form so that it can be pressed to shape between the 10 crown block and the brim board or block so that the latter two fit together perfectly and the entire blocking form may be made up more quickly and at a consequent saving in cost.

Heretofore in the construction of hat block assemblies, it has been the practice to cut the band block out of a solid piece of wood or other material and grind or carve it down until it conforms to the shape of one side of 20 the crown block and the shape on the opposite side of the brim board or block with the result that considerable time was necessary and care had to be taken in the making of each band block to make it fit between the crown 25 and brim block in connection with which it was to be used.

The object of my invention is to make the band block of a laminated structure, the parts of which are glued together and compressed between the crown block and brim block to conform to the shape thereof.

My invention contemplates the use also of the band block for use as a crown lifter or crown base when the brim block is not used 35 in connection with the crown block in which event, one side of the band block may be ground flat after it has been shaped to conform to the under surface of the crown block.

I also contemplate the use of the band 40 block or brim block with or without a crown or collar and the band block may be either larger or smaller in diameter than the crown block to provide for the overlap of the hat brim and the crown or vice versa and it may be further provided with cord grooves for 45 readily blocking hats on the crown block. The band block may also be flat on both sides and due to its plastic or laminated form will be superior to the ordinary band block as it 50 will not warp and will conform exactly to

the crown and brim. While I have not illustrated it, I contemplate the use of a plastic element which may be in laminated form or may be single and which may be nailed or otherwise fastened down, steamed or dried 55 into shape.

With these and other objects in view, my invention comprises the construction, combination and arrangement of the various parts hereinafter described, and then particularly pointed out in the appended claims.

In the drawing:

Figure 1 is a view in side elevation of a hat block assembly, the band block of which is constructed in accordance with my invention.

Figure 2 is a plan view of the brim board or block having mounted thereon, the band block as illustrated in Figure 1, the crown block being omitted for the purpose of illustrating the relative position of the band block 70 on the brim block.

Figure 3 is a section taken on the line 3—3 of Figure 2 and illustrates the shape in cross section of the band block.

Figure 4 illustrates the first step in the process of building up a laminated structure and the gluing of the parts together.

Figure 5 shows the second step in the process which consists in shaping the structure in a press or vise between the parts of the hat block or between suitable shaping members.

Figure 6 is a view in elevation showing how the band block is used as a crown lifter or base, the crown block being shown in connection therewith, and

Figure 7 is a fragmentary view in section showing how the laminated structure comprising the band block may be of smaller diameter than the crown block to provide for the overlap of the hat brim and the crown portion thereof.

Referring to the drawing in detail, 5 indicates a crown block which is usually made from solid wood, the lower or bottom surface of which, as indicated by the numeral 6 is shaped to conform to the style of hat that is to be blocked thereon. The numeral 7 indicates the brim board or block upon which is 95 100

shaped the brim of the hat and this member also is made preferably of solid wood to which a high polish has been given and in which are provided the guide pins 8 which extend into suitable openings 9 provided in the crown block. The band block 10 is interposed between the crown block 5 and the brim block 7 and may be of any thickness desired and of any shape either in longitudinal or transverse cross section.

The method of making the band block and of shaping the same is the important feature of my invention and the first step in the process of making the band block is the building up of a series of thin, sheet-like members 7 made of wood or other suitable material to form a laminated or plastic structure 12, as illustrated in Figure 4, the parts thereof being glued or steamed or nailed together. This structure 12 is then placed between a crown block 5 and a brim block 7, the opposing edges of which are of any desired shape and the hat block is placed in a suitable vise 13 until the members 5 and 7 are drawn securely against the opposite faces of the band block 10 so that the same is bent to the shape conforming to the faces of the crown block and brim block and the hat block is maintained in the vise until the band block has thoroughly dried and retains the shape conforming with the crown block and brim block in connection with which it is to be used. Either before or after the shaping of the laminated structure 12 constituting the band block 10, the same may be provided with the finger hole openings 14 and dowel pin openings 15 so that it can be placed in proper position over the pins 8 and can be readily handled through the finger hole openings 14.

In adapting the laminated structure for use as a crown base, the same may be first bent to shape between a crown block and a brim board or block after which, as illustrated in Figure 6, it may be shaved off flat on one side as at 16 so that it will rest on a flat surface.

When the laminated structure is to serve as a crown lifter between the crown block 5 and the brim block 7, its diameter may be slightly decreased to provide room for the band of the hat which, in the construction of hats of the usual type, forms a part of the hat rim 17 over which is placed the crown of the hat 18 for blocking, or the brim band is sometimes placed over the crown.

The thickness of the band block 10 will depend upon how wide the band 19 of the hat is to be. In shaping the laminated structure, it need not necessarily be placed between a crown block and a brim block but may be placed between any two members that will give it a suitable shape for use between the crown and brim block.

It is evident that I have provided a band block which may be of any particular shape

in cross section, either longitudinally or transversely, may be of an inverted saucer shape or as illustrated in Figure 1. Also, the laminated member can be flat on either side which is accomplished by pressing the laminated structure to any shape and then cutting or grinding either side flat which structure occurs when the band block is to be used as a base for a crown block only.

It is evident also that in the use of my improved laminated band block, considerable labor is saved in that the solid band blocks are dispensed with and the time taken to grind the surfaces thereof down to fit between the crown and brim block is dispensed with. In my construction, it is simply necessary to build up laminations or plastic mass to the required thickness, glue or mould them and then press them to the desired shape, either in a form for the purpose or between the blocks in connection with which it is to be used and the band blocks may be pressed in any shape desired.

My invention is not to be restricted to the precise details of construction shown since various changes and modifications may be made therein without departing from the scope of the invention or sacrificing the advantages derived from its use.

What I claim is:—

1. The method of making a unit of a hat block assembly which consists in building up a laminated structure and then shaping the same under pressure between shaping members, including the crown and brim portions of a hat block.

2. The method of making a unit of a hat block assembly which consists in building up an intermediate crown lifter structure and then shaping the same under pressure between shaping members.

3. The method of making a unit of a hat block assembly which consists in building up a laminated structure and then shaping the same under pressure to the shaped surface of one of the members of a hat block assembly.

Signed at New York in the county of New York and State of New York this 25th day of July, A. D. 1930.

HARRY E. GOUGH. [L. S.]
